UNITED STATES PATENT OFFICE.

WORRALL S. KELLY, OF CHICAGO, ILLINOIS.

EXCAVATING AND SCOOP SHOVEL.

Application filed May 18, 1925. Serial No. 30,921.

To all whom it may concern:

Be it known that I, WORRALL S. KELLY, a citizen of the United States, residing at Chicago, in the county of Cook and State 5 of Illinois, have invented certain new and useful Improvements in Excavating and Scoop Shovels, of which the following is a specification.

This invention has to do with improvements in power-operated shovels for excavating, and particularly for scoop work. The shovel herein disclosed is particularly intended for use in that class of work in which the shovel is first given a more or less horizontal movement to scoop up the material, and is afterwards raised so as to carry the material to a desired point where it is dumped.

The main object of the invention is to 20 provide a device of the foregoing character which is so constructed that in the horizontal scooping operation, it will naturally tend to bite into the surface of the earth so as to ensure a speedy filling of the scoop, without, 25 however, being subject to an excessive amount of biting action such as would tend to jam the front of the shovel and tend to cause it to turn over.

A further feature of the invention relates 30 to the provision of an extremely simple construction and one which may, if desired, be made from a single casting or as a solid rigid structure of the built-up form.

Another object of the invention is to provide 35 a device of the foregoing character which has its front portion so constructed that it will act very much as a plow in entering into and breaking up the material sought to be excavated. This will not only 40 improve the scooping action itself, but will also considerably facilitate the operation of the device and make it possible to do its work at a greatly reduced power consumption.

Another feature of the invention relates 45 to the provision of improved means for sustaining the front portion of the device when it is raised so as to retain the material therein until the device has been moved 50 to the proper dumping position.

Other objects and uses of the invention will appear from a detailed description of the same which consists in the features of construction and combinations of parts hereinafter described and claimed.

In the drawing:

Figure 1 shows a side perspective view of a scoop embodying the features of the present invention, the lifting chains being shown in position and the towing and dumping 60 ropes being shown in the position which they occupy during the excavating and carrying operations.

Fig. 2 shows a plan view corresponding to Fig. 1; and

Fig. 3 shows a front elevation corresponding to Figs. 1 and 2.

My improved scoop includes generally a body 4 having a floor 5 the rear portion of which is curved upwardly as shown at 6 in Fig. 1, and continues on upwardly to establish a back wall 7 as shown in Fig. 3. The extreme upper edge of this back wall is then preferably curved forwards as shown at 8 so as to prevent the material from overflowing at the upper edge of the back wall portion during the scooping operation.

Reaching from the floor 5 are the sides 9 and 10. These preferably extend up to an elevation substantially equal to that of the upper curved portion 8 of the back wall. The front portion of the floor 5 is preferably extended forward as shown in the different figures to establish a plow point or the like 75

11. This plow point has its extreme front pointed portion 12 turned down somewhat as best shown in Figs. 1 and 3, so that it will bite into and open up the furrow of material which is to be taken into the scoop. Immediately behind this pointed portion 85

there is an upstanding arm 13 which reaches up to a position somewhat above the center of the height of the scoop and is then carried forwardly in a substantially horizontal direction—that is parallel to the flat portion 5 of the floor, as a beam 14 in Fig. 1. This horizontally extending beam 14 preferably reaches to a position somewhat in advance of the cutting point 12, its extreme front portion 90

being provided with a suitable eyelet 15 for the tow and control ropes. The front edge of the arm 13 is preferably somewhat sharpened as clearly shown in Fig. 3, so as 95

to assist in breaking the excavated material and throwing it to both sides of the arm so that the two sides of the scoop will be equally filled.

On a line above and somewhat behind the center of gravity of the scoop when filled, I provide the pins 16 and 17 to which may be 110 attached the lifting chains 18 and 19, respectively, by the use of eyes. The upper

portions of these chains 18 and 19 are brought together at a common eye to which may be attached a lifting rope or chain 21. Preferably a spacer bar 22 extends between the chains 18 and 19 at a point above the scoop, said bar being of sufficient length to hold the lower portions of the chains at such a degree of separation that they do not materially interfere with the tilting and manipulation of the scoop itself.

The tow rope 23, which usually pulls in a substantially horizontal direction, may be connected to the eye 15 by means of a chain 24. A control rope 25 also reaches from the eye 15 upwards and backwards at an angle of about 60 degrees and then passes over a pulley 26 and again forwardly as shown in Fig. 1. The pulley 26 in turn is conveniently placed on the front end of a short section 20 of rope or chain 27 which is, in turn, connected to the eye 20 already referred to.

When towing exclusively by the use of the rope 23, the rope 25 being relatively slack, the front edge of the scoop will tend to bite 25 down into the material so as to insure an ample biting operation resulting in a complete filling of the scoop. If desired, this biting operation may be somewhat controlled by the use of the rope 25, tension upon which 30 tends to raise the front edge and restrict the biting action.

After the scoop is filled, it may be raised by the use of the chain or rope 21, the tension on the control rope 25 being regulated 35 so as to prevent the front edge of the scoop from tipping sufficiently to allow material to be discharged until the desired time; then by easing off the rope 25 the front edge of the scoop will fall on account of the rearward position of the pivotal points 16 and 40 17, resulting in a desired dumping.

Both of the tow and control ropes may be manipulated in any convenient manner, as, for example, by the use of one or more drums 45 28 located in advance of the position of the scoop itself.

By providing a plow point which merges rearwardly into a relatively thin upstanding fin which furnishes a central division wall 50 for the scoop, the material will be diverted laterally and evenly into both sides of the scoop, and at the same time such fin will act like an upstanding keel to prevent lateral slewing of the scoop and maintain its straight line of travel when drawn forward from a single center connection, which arrangement obviates the necessity of using a front-bail and side-connections of the character commonly employed in the art.

60 The formation of these portions of the scoop is such that smooth rounded side-surfaces are provided at all points, which facilitate both the ingress and egress of the material, no sharp angles or shoulders being afforded for the lodgment of material

while the scoop is being dumped. Furthermore, the arrangement is one which affords a very substantial reinforcement and stiffening for the bottom and front edge of the scoop, and the plow point facilitates 70 the cutting action and facilitates the advance of the scoop through hard or stony ground in which small boulders, cobblestones, or débris are embedded, and in which a broad straight cutting edge of the usual 75 type would encounter such resistance as might stall the advance of the scoop or result in distortion or breakage. In ground of this character the sharp pointed toe of the plow will serve to pry loose such 80 boulders or pieces of débris and lift them upwardly or thrust them laterally in such a way as to permit the continued advance of the scoop without substantial interference.

While I have herein shown and described only a single embodiment of the features of my present invention, still I do not intend to restrict myself to the same except as I may do so in the claims. Nor, unless otherwise 90 indicated in the claims, do I limit myself to any particular size of shovel, nor to the particular arrangement of cables shown and described, nor to the use of any particular power for operating the shovel, since the shovel in proper sizes is adapted to various classes of work with suitable connections of such type as are adapted to control the operation of the shovel in conformity with principles well understood in the art.

I claim:

1. A shovel of the class described, comprising a scoop-shaped body having a floor, side walls and a back wall, the floor having upstanding therefrom a centrally located cutting member plow-shaped along its front edge and merging rearwardly into a centrally disposed upstanding fin and merging upwardly into a forwardly extending beam, lifting connections secured to the side walls 105 of the body and upwardly extending therefrom, a draft connection secured to the forward end of the beam, and a control connection extending upwardly from the beam, substantially as described.

2. A shovel of the class described, comprising a scoop shaped body having a floor, side walls and a back wall, the floor having upstanding therefrom a centrally located cutting member plow-shaped along its front edge and merging rearwardly into a centrally disposed upstanding fin and merging upwardly into a forwardly extending beam, lifting connections secured to the side walls of the body and upwardly extending therefrom, a draft connection secured to the forward end of the beam, a control connection extending upwardly from the beam, and a pulley around which said control connection is passed to bring the forward end of 120 125 130 135 140 145 150 155 160 165 170 175 180

said connection into substantial parallelism with the draft connection, substantially as described.

3. A shovel of the class described, comprising a scoop shaped body having a floor, side walls and a back wall, the floor having upstanding therefrom a centrally located cutting member plow shaped along its front edge and merging rearwardly into a centrally disposed upstanding fin and merging upwardly into a forwardly extending beam, lifting connections secured to the side walls of the body and upwardly extending therefrom, a draft connection secured to the forward end of the beam, a control connection extending upwardly from the beam, substantially as described.

4. A shovel of the class described, comprising a scoop shaped body having a floor, side walls and a back wall, the floor having upstanding therefrom on its front portion a centrally disposed plow shaped cutting member having a forwardly and downwardly pointed centrally disposed toe behind which the side walls of the cutting member flare laterally and backwardly to the floor, said forward portion merging rearwardly into an upstanding centrally disposed fin, and said cutting portion merging upwardly and forwardly into a horizontally extending beam portion extending forwardly to a point in advance of the cutting toe, lifting connections secured to the side walls of the body and upwardly extending therefrom, and a draft connection secured to the forward end of the beam, substantially as described.

5. A shovel of the class described, comprising a scoop shaped body having a floor, side walls and a back wall, the floor having upstanding therefrom on its front portion a centrally disposed plow shaped cutting member having a forwardly and downwardly pointed centrally disposed toe behind which the side walls of the cutting member flare laterally and backwardly to the floor, said forward portion merging rearwardly into an upstanding centrally disposed fin, and said cutting portion merging upwardly and forwardly into a horizontally extending beam portion extending forwardly to a point in advance of the cutting toe, lifting connections secured to the

side walls of the body and upwardly extending therefrom, a draft connection secured to the forward end of the beam, and a control connection extending upwardly from the beam, substantially as described.

6. A shovel of the class described, comprising a scoop shaped body having a floor, side walls and a back wall, the floor having upstanding therefrom on its front portion a centrally disposed plow shaped cutting member having a forwardly and downwardly pointed centrally disposed toe behind which the side walls of the cutting member flare laterally and backwardly to the floor, said forward portion merging rearwardly into an upstanding centrally disposed fin, and said cutting portion merging upwardly and forwardly into a horizontally extending beam portion extending forwardly to a point in advance of the cutting toe, lifting connections secured to the side walls of the body and upwardly extending therefrom, a draft connection secured to the forward end of the beam, a control connection extending upwardly from the beam, and a pulley around which said control connection is passed to bring the forward end of said control connection into substantial parallelism with the draft connection, substantially as described.

7. A shovel of the class described, comprising a scoop shaped body having a floor, side walls and a back wall, the floor having upstanding therefrom on its front portion a centrally disposed plow shaped cutting member having a forwardly and downwardly pointed centrally disposed toe behind which the side walls of the cutting member flare laterally and backwardly to the floor, said forward portion merging rearwardly into an upstanding centrally disposed fin, and said cutting portion merging upwardly and forwardly into a horizontally extending beam portion extending forwardly to a point in advance of the cutting toe, lifting connections secured to the side walls of the body and upwardly extending therefrom, a draft connection secured to the forward end of the beam, a control connection extending upwardly from the beam, a pulley around which said control connection is passed to bring the forward end of said control connection into substantial parallelism with the draft connection, and means for connecting said pulley to the lifting connections substantially as described.

WORRALL S. KELLY.
